US0D1060066S

(12) **United States Design Patent** (10) **Patent No.:** **US D1,060,066 S**
(45) **Date of Patent:** **** Feb. 4, 2025**

(54) **TRACKING DEVICE**

(71) Applicant: **HTC Corporation**, Taoyuan (TW)

(72) Inventors: **Pei-Pin Huang**, Taoyuan (TW);
Chang-Hua Wei, Taoyuan (TW)

(73) Assignee: **HTC CORPORATION**, Taoyuan (TW)

(**) Term: **15 Years**

(21) Appl. No.: **29/901,764**

(22) Filed: **Sep. 5, 2023**

(51) **LOC (15) Cl.** **10-04**

(52) **U.S. Cl.**

USPC **D10/70**

(58) **Field of Classification Search**

USPC ..... (57) **CLAIM**

The ornamental design for a tracking device as shown and described.

DESCRIPTION

FIG. 1 is a perspective view of a tracking device in accordance with our new design;

FIG. 2 is a front view thereof;

FIG. 3 is a rear view thereof;

FIG. 4 is a left view thereof;

FIG. 5 is a right view thereof;

FIG. 6 is a top plan view thereof;

FIG. 7 is a bottom plan view thereof; and,

FIG. 8 is another perspective view thereof.

The broken lines in the drawings depict portions of the tracking device that form no part of the claim.

1 Claim, 8 Drawing Sheets
